Term of patent 14 years

(Cl. D64—11)

FIG. 3.

FIG. 4.

FIG. 5.

Figure 1 is a side perspective view of a calculating machine, showing my new design;

Figure 2 is a plan view;

Figure 3 is a front elevational view;

Figure 4 is a rear elevational view; and

Figure 5 is a side elevational view showing the side visible in Figure 1.

The side opposite the one shown in Figure 5 is substantially similar in design.

The broken line illustration of the roll of tape shown in Figs. 1, 2, 3 and 5 is for illustrative purposes only.

I claim:

The ornamental design for a calculating machine, as shown and described.
